UNITED STATES PATENT OFFICE.

FRANK H. WARREN, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

METHOD FOR USE IN THE MANUFACTURE OF SHOES.

Application filed February 24, 1920. Serial No. 360,691.

To all whom it may concern:

Be it known that I, FRANK H. WARREN, a citizen of the United States, residing at Swampscott, in the county of Essex and 5 State of Massachusetts, have invented certain Improvements in Methods for Use in the Manufacture of Shoes, of which the following description, in connection with the accompanying drawings, is a specification, 10 like reference characters on the drawings indicating like parts in the several figures.

This invention relates to methods for use in the manufacture of boots and shoes and 15 particularly to methods of lengthening soles, the present method being especially applicable to lengthening block soles.

The present high cost of shoe materials, particularly shoe leather, has rendered it 20 necessary to employ every possible expedient consistent with the production of a serviceable and saleable product for economizing in expensive material.

An object of the present invention is to 25 provide an improved method of lengthening soles so that soles intended for one size of shoe may be rendered available for shoes of a larger size and at the same time to improve the soles in some respects without detracting 30 in any way from their serviceability.

In the practice of the present invention a sole is cut in two transversely in such a manner that when one of the parts is reversed and placed in abutting relation to the other 35 part the total length of the sole will be increased and a recess will be formed on one face of the sole suitable to be filled with cheap or scrap material to form a sole of uniform thickness and of increased length.

40 The abutting portions of the sole as well as the portions of the sole which abut the filling piece and the filling piece itself are preferably formed at an angle to the plane of the tread face of the sole such that when 45 pressure is applied to the sole, for instance in the heelng operation, all the joints between the parts will be closed and "checking" or opening of the joints between the abutting faces will be avoided. Convenient-

ly and as shown herein, the sole is cut from 50 the grain side in a plane transverse to the sole and inclined upward and toward the rear part of the sole this cut being located somewhat at the rear of the breast line, and is cut by a similar transverse cut extending 55 from the flesh side and having an inclination downward and toward the rear of the sole substantially equal to the inclination of the first cut. The said cuts are preferably connected by a transverse cut parallel to the 60 sole faces and located half way between them, the length of this cut longitudinally of the sole and the distance between the first cuts at the center of the sole being equal to the amount which it is desired to lengthen 65 the sole. It will be understood, of course, that the cuts described may be made in any order or simultaneously. The severed rear portion of the sole is turned the other side up relatively to the other part of the sole 70 and the face of the rear part of the sole, formed by the first cut, is placed in abutting relation to the face of the forward part of the sole formed by the second cut. The placing of the parts in this position lengthens the sole by the amount of longitudinal 75 separation of the first two cuts and forms on the bottom of the sole a recess, half as deep as the sole thickness, having inclined front and rear walls. An appropriate filling 80 such as a suitably formed filling piece is placed in this recess to restore the sole to uniform thickness and is secured to the parts of the sole by any suitable means, for example by cement or by staples placed preferably in position to straddle the joints of the 85 sole parts.

In the drawing,

Fig. 1 is a perspective view representing a block sole flesh side up with its rear portion 90 severed by a transverse cut made in accordance with the present invention;

Fig. 2 is an exploded view in perspective of the rear part of the sole with one portion reversed so as to be grain side up and showing the filling piece which is inserted in the recess formed by the reversal of the rear part of the sole.

Fig. 3 is a perspective view of the rear end of the lengthened sole with the parts thereof secured together, the heel and the final outline of the sole being shown in dotted lines; 5 and

Fig. 4 is a side view of the rear end portion of a shoe made with the lengthened sole of the present invention.

In the practice of the method of the 10 present invention a sole is taken as it comes from the cut sole manufacturer, for instance a block sole 2, as shown in Fig. 1. It will be noted that such a sole is cut only at the 15 sides to approximate the final contour of the sole, the ends being left with substantially square corners. The sole 2 may be first cut, as at 4, transversely in a plane inclined upwardly and toward the rear of the sole, this cut extending from the grain side half way 20 through the sole. A similar cut may be made from the flesh side, as at 6, half way through the sole in a direction inclined downwardly and toward the rear of the sole, the direction of this cut being at an 25 angle to the tread face of the sole equal and opposite to that of the first cut. The second cut is spaced from the first cut longitudinally of the sole a distance equal to the amount it is desired to lengthen the sole. 30 This usually will be half or three quarters of an inch, this amount being sufficient to enable a sole intended for a given size of shoe to be used for shoes two or three sizes larger. The two cuts described are then 35 connected by a transverse cut 8 parallel to the face of the sole and located half way between them, the sole being thus completely severed.

It is to be understood that in the description 40 of the operation of severing the sole the cuts are explained in a given order merely for the purpose of illustration and that these cuts may be made in any order or simultaneously, importance being attached 45 only to the extent of the cuts and the positions of the planes, relatively to the sole, in which they are made.

The sole having been thus severed, one 50 part, for example the rear portion 10, is reversed in position and its original lower beveled face or end is placed in abutting relation to the upper beveled face or rear end of the forward part. Since the two cuts first described were made at equal and opposite 55 inclinations to the general plane of the sole, the inclination of the end of the forward part of the sole made by the cut 6 will correspond to that of the end face on the rear part 10 formed by the cut 4 and a tight 60 joint between the ends of the sole parts will be formed. In Fig. 2 the sole parts and a filling piece 12 are shown ready to be assembled by movement of the parts 10 and 12 lengthwise of the sole in the manner shown 65 in Fig. 3. The recess on the under side of

the sole formed by reversing the rear part has parallel side walls at an inclination to the tread face of the sole, one wall being formed by the cut 4 on the forepart of the sole and the other formed by the cut 6 on the rear part. The filling piece 12 is prepared of 70 scrap leather, leatherboard, or other suitable material of a size to fill the recess and is inserted in the recess, as shown in Fig. 3.

The parts of the sole thus assembled may 75 be held together by cement or by staples or by both. As shown a plurality of staples 14 are driven across each transverse joint of the sole which staples securely hold the parts together. The sole now has a length 80 greater than that of the original sole by half the width of the filling piece and for practical purposes is as good as an integral sole of the same length. All the transverse joints of the sole are at an angle to the plane 85 of the sole so that when pressure is applied to the sole perpendicular to its face, as for instance in the operation of nailing on the shoe heel, the joints tend to close and any 90 tendency of the joints to check or open up in this or subsequent operations on the shoe is avoided. The relation of the joints as 95 they appear outside of the sole after the heelng operation is shown in Fig. 4 where they are given exaggerated prominence for the purpose of illustration, it being understood that when the heel and rear portion of the sole are trimmed and finished they become invisible.

It will be seen that the reversed rear end 100 of the sole is grain side up. Consequently about the rear end of the shoe and for a distance on each side of the heel the sole presents a grain face on one side of the rand 105 crease of which the upper forms the other side. This is of importance since a much better finish in the rand crease may be secured than where the sole presents a flesh face in the rand crease, as in the case with a sole which is not lengthened in accordance 110 with the present invention.

Having thus described my invention, what I claim as new and desire to secure by Letters Patent of the United States is:

1. That improvement in methods of 115 lengthening soles which consists in severing the sole at the rear of the breast line of the heel by a cut extending transversely of the sole, the adjacent edges of the cut on the grain side extending across that side of the sole adjacent to but at the rear of the breast line, the adjacent edges of the cut on the flesh side extending across that side parallel to said first edges and disposed a material 120 distance toward the rear of the sole therefrom, one of said cuts being extended to meet the other cut, then turning one portion of the sole the opposite side up relatively to the other portion, placing the severed ends in abutting relation, filling the trans- 125

verse recess in the sole thus formed with suitable material, and securing the parts together.

2. That improvement in methods of 5 lengthening soles which consists in cutting the sole half way through from the grain side in a direction transversely of the sole on a line located at the rear of the heel breast, cutting the sole half way through 10 from the flesh side parallel with the first cut on a line disposed a substantial distance toward the heel end of the sole, connecting the two cuts by a cut parallel with the tread face of the sole completely to sever the sole, 15 reversing one of the parts, placing the ends in abutting relation, filling the recess in the sole thus formed, and securing the parts together to form a completed sole of greater length and having a grain surface on the 20 portion of the sole next the heel seat of the shoe and a grain surface on the forepart of the sole.

3. That improvement in methods of 25 lengthening soles which consists in severing the rear part of the sole by a cut extending transversely of the sole and from the grain side in a plane inclined toward the rear of the sole half way through the sole, thence parallel to the bottom face of the sole for 30 a distance equal to the amount the sole is to be lengthened and thence toward the top face of the sole in a plane inclined toward the forward part of the sole, the inclination being equal to the rearward inclination 35 of said first portion of the cut, then reversing the severed rear portion, abutting the severed ends filling the transverse recess thus formed, and securing the parts together to form a lengthened sole of the 40 thickness of the original sole.

4. That improvement in methods of 45 lengthening soles which consists in severing a sole by a transverse cut extending from a face of the sole part way through from one side, thence parallel with the faces of the sole for a substantial distance and thence out to the other side of the sole, reversing one of the parts relatively to the other, abutting the cut faces, filling the recess in the sole, and securing the parts together.

5. That improvement in methods of 55 lengthening soles which consists in severing a sole by a transverse cut extending from edge to edge of the sole half way through the sole from the grain side in an upward and rearward direction, thence parallel with the face of the sole for a substantial distance and thence out to the flesh side of the sole in an upward and forward direction, reversing one of the parts relatively to the other, abutting the cut faces, inserting a filling piece in the recess in the sole, and securing the parts together.

6. That improvement in methods of

lengthening soles which consists in severing the sole by straight cuts transversely of the sole in such manner that when one part of the sole is reversed with respect to the other part and the ends abutted the sole will be 70 lengthened and a recess formed, then reversing one of the parts, abutting the severed ends, and securing a filler in the recess to restore the sole to uniform thickness throughout its area. 75

7. That improvement in methods of lengthening soles which consists in severing the rear portion of the sole by a cut portions of which are obliquely inclined to the planes of the top and bottom faces of the 80 sole, reversing one of the severed parts relatively to the other, abutting the parts, and securing a filling piece in the recess thus formed in the sole.

8. That improvement in methods of 85 lengthening soles which consists in severing a sole on transverse planes two of which are at right angles to each other, reversing one part of the sole relatively to the other, abutting the ends, restoring the sole to uniform thickness, and securing the parts together.

9. That improvement in methods of 90 lengthening soles which consists in severing a sole on transverse planes one of which 95 is parallel to the top and bottom faces of the sole, reversing one of the parts, abutting the ends, and restoring the sole to uniform thickness.

10. That improvement in methods of 100 lengthening soles which consists in severing a sole on transverse planes two of which are equally and oppositely inclined to the top and bottom faces of the sole and one of which is parallel to said faces, reversing one of said parts relatively to the other, abutting their cut ends, and restoring the sole to uniform thickness. 105

11. That improvement in methods of 110 lengthening soles which consists in severing a sole on transverse planes two of which are inclined to the top and bottom faces of the sole, reversing one of the parts, abutting the cut ends, and restoring the sole to uniform thickness by the addition of suitable material. 115

12. That improvement in methods of 120 lengthening soles which consists in severing a sole on transverse planes in zigzag relation to each other, reversing one of the parts relatively to the other, abutting the ends, restoring the sole to uniform thickness, and securing the parts together.

13. That improvement in methods of 125 lengthening soles which consists in severing the sole by a cut in three planes, one plane being parallel to the top and bottom faces of the sole and the other planes being inclined to said parallel plane, reversing one of the severed portions relatively 130

to the other, abutting the cut ends, and restoring the thickness of the sole.

14. That improvement in methods of lengthening soles which consists in severing a sole by a transverse cut so located that when one part of the severed sole is reversed with respect to the other part and

the cut ends abutted the sole will be lengthened and a recess formed, reversing one part, abutting the ends, and filling the recess to restore the sole to uniform thickness. ¹⁰

In testimony whereof I have signed my name to this specification.

FRANK H. WARREN.
